(57) **CLAIM**

The ornamental design for a respiratory conduit end cap, as shown and described.

DESCRIPTION

FIG. 1 is a top, front and right-side perspective view of a respiratory conduit end cap embodying our new design; FIG. 2 is a front view thereof;

FIG. 3 a rear view thereof;

FIG. 4 is a left-side view thereof;

FIG. 5 is a right-side view thereof;

FIG. 6 is a top view thereof; and,

FIG. 7 is a bottom view thereof.

The dash-dash broken lines are used to illustrate portions of the respiratory conduit end cap that form no part of the claimed design. The dot-dash broken lines are used to illustrate the boundaries of the claimed design and form no part thereof.

1 Claim, 7 Drawing Sheets
